UNITED STATES PATENT OFFICE.

DAVID ROBERTS, OF GRANTHAM, ENGLAND.

INTERNAL-COMBUSTION ENGINE.

No. 853,422.

Specification of Letters Patent.

Patented May 14, 1907.

Application filed August 28, 1905. Serial No. 276,155.

To all whom it may concern:

Be it known that I, DAVID ROBERTS, a subject of the King of Great Britain, residing at Spittlegate Iron Works, Grantham, in the county of Lincoln, England, have invented new and useful Improvements in Internal-Combustion Engines, of which the following is a specification.

My invention relates to internal combustion engines of the kind wherein liquid hydrocarbon is injected into a compressed charge of air and mixed therewith so as to form an explosive mixture, and chiefly to such engines as rely upon the heat of the walls of the explosion chamber for igniting the successive charges. In engines of this class as hitherto constructed, difficulty has been experienced in efficiently spraying or atomizing the hydrocarbon and thoroughly mixing it with the air in the short time available at or near the end of the compression stroke, with the result that the efficiency of the engine has been more or less impaired; especially is this the case in engines where the explosions do not take place with uniformity as the missing of one or more explosions allows of the explosion chamber cooling to such an extent as to fail to ignite the charge.

30 I have found by experiment that if the hydrocarbon is thoroughly commingled with the air at the right moment, the explosions will take place with regularity, notwithstanding the cooling of the combustion chamber.

My invention, therefore, chiefly comprises improved means for effecting the spraying of the oil, whereby a considerable economy in oil and increased efficiency in the working of the engine are attained.

According to my invention I combine with the nozzle through which the oil is ejected an apparatus for causing a jet or current of air to impinge against the oil jet and thoroughly pulverize and break up the same, the air current serving at the same time to create so much commotion or agitation in the combustion chamber that the particles of hydrocarbon vapor are immediately carried to all parts of the same to produce the desired mixture.

Figure 1 is a sectional elevation of apparatus arranged in accordance with my invention, the said figure including a portion of the combustion chamber of the engine to which the spraying device is attached. Fig.

2 is a plan of said mechanism, and Fig. 3 is a section on line 3—3, Fig. 2.

In the drawings *a* is the oil jet apparatus which is connected with a force pump in the usual manner and *b* is the nozzle through which the oil is ejected.

c is a box which is attached to the combustion chamber *c'* of the engine and which is provided with the flaring chamber or passage *d*. The box *c* is clamped in position between the nozzle and the combustion chamber by studs *d'* secured to the flange of said combustion chamber and passing through a flange *a'* on the fitting *a*.

The box *c* is provided with the passage *e* through which the compressed air is delivered, the said passage terminating, as shown, in the annular slit *f* formed in the wall of the chamber *d* adjacent to the nozzle *b*, the air delivered through the said slit serving, by impinging against the oil jet, to thoroughly pulverize and break up the same in the desired manner. As shown in the drawing the slit *f* is formed by recessing the face of the box *c* and then inserting a plate *g* into the recess, leaving sufficient space for the passage of the air.

Any suitable means may be employed for admitting the air periodically; as shown in the drawing, a valve *h* is arranged in the passage *e*, the base of the said valve being acted upon by the face of a cam-like plug *i* which is oscillated in any suitable manner, for instance, through the medium of a spindle *i'* passing through a stuffing box *i''* and connected by a lever *i'''* and rod *i''''* to some moving part of the engine.

In practice, I advantageously so regulate the emission of the oil that each charge is projected from the jet in a manner resembling that in which a projectile leaves a gun, and I so regulate the air jet that it commences to flow immediately before the issue of the oil, so that as the oil issues, it is directed into the vortex produced by the air jets and so instantly pulverized in the manner hereinbefore described.

Instead of forming a slit *f* as hereinbefore described it is to be understood that a hole or a series of holes may be formed through which the air will enter the chamber *d*.

As hereinbefore stated the thorough commingling of the hydrocarbon with the air at the right moment allows of a certain amount of cooling of the combustion chamber, with the arrangement described however, I am

able to utilize the heat produced by the compression of the air during the compression stroke for augmenting the heat of the walls of the combustion chamber.

5 Having now particularly described and ascertained the nature of my said invention and in what manner the same is to be performed, I declare that what I claim is:-

1. In an internal combustion engine, the combination with a combustion chamber having an opening therein, of a box having a flaring passage therein, said passage in said box having one end directly in line with and in communication with the opening in said

15 combustion chamber, an oil jet directly in line with and in communication with the other end of said passage, said box being provided with a port opening into said flaring passage for admitting compressed air and

20 directing the same across the path of the oil ejected from said jet, substantially as described.

2. In an internal combustion engine, the combination with a combustion chamber having an opening therein, of a box having a flaring passage therein, said passage in said box having one end directly in line with and in communication with the opening in said combustion chamber, an oil jet directly in

25 line with and in communication with the other end of said passage, said box being provided with an annular slit around said flaring passage adjacent to said oil jet and means for forcing compressed air through said slit into

30 said passage whereby the compressed air is directed across the path of the oil ejected from said jet, substantially as described.

3. In an internal combustion engine, the

combination with a combustion chamber having an opening therein, of a box having a flaring passage therein, said passage in said box having one end directly in line with and in communication with the opening in said combustion chamber, an oil jet directly in line with and in communication with the other end of said passage, said box being provided with an annular slit around said flaring passage adjacent to said oil jet, the walls of said slit being inclined and means for forcing compressed air through said slit into said flaring passage, whereby the compressed air is directed across the path of the oil ejected from said jet and toward the combustion chamber, substantially as described.

4. In an internal combustion engine, the combination with a combustion chamber having an opening therein, of a box having a flaring passage therein, said passage in said box having one end directly in line with and in communication with the opening in said combustion chamber, an oil jet directly in line with and in communication with the other end of said passage, said box being provided with a compressed air passage communicating with the interior of said flaring passage and adapted to direct the compressed air across the path of the oil ejected from said oil jet, a valve seated in said compressed air passage, said valve normally closing said passage and means for automatically opening said valve, substantially as described
